Primary Examiner — Catherine Ho(74) *Attorney, Agent, or Firm* — Kilpatrick Townsend & Stockton LLP(57) **CLAIM**

The ornamental design for a directional sign for evacuation, as shown and described.

DESCRIPTION

FIG. 1 is a top plan view of the first embodiment of a directional sign for evacuation showing our new design; FIG. 2 is a top plan view of the second embodiment of a directional sign for evacuation; and,

FIG. 3 is a top plan view of the third embodiment of a directional sign for evacuation.

The broken lines depict portions of the directional sign for evacuation that form no part of the claimed design.
